UNITED STATES PATENT OFFICE.

JOHN A. EVANS, OF RICHMOND, INDIANA.

DETACHABLE BRACKET.

Application filed June 12, 1922. Serial No. 567,524.

To all whom it may concern:

Be it known that I, JOHN A. EVANS, a citizen of the United States, residing in the city of Richmond, in the county of Wayne, 5 State of Indiana, have invented new and useful Detachable Brackets, of which the following is a full, clear, and comprehensive specification and exposition, the same being such as will enable others to make and 10 use the same with exactitude.

This present invention relates more particularly to green-house devices, for utilitarian purposes, but it may with aptitude be employed in many other places, such as 15 in homes or in flower stores, it may be employed for various purposes other than for the display of plants and flowers if desired.

The object of this invention, broadly speaking, is to provide detachable brackets 20 which are simple in construction, neat and attractive in appearance, easily attached or detached with relation to operative position, and which can be manufactured and sold at a comparatively low price.

25 The particular object is to provide a construction including a body which may be secured to an upright post, such as tubing, and having a plurality of instantly attachable and detachable arms, by which a great 30 variety of combinations may be arranged to accommodate various eventualities in the display of plants and the distribution thereof whereby they will receive the proper light and air and at the same time being arranged 35 to give the maximum of artistic appearance.

The preferred means for carrying out the principles of my invention in a practical manner is shown in the accompanying drawings, in which—Figure 1 is a top plan view 40 of the body alone. Figure 2 is an inside-face view or elevation of one member of the body, the two body members being identical with each other, but they are oppositely disposed in practice. Figure 3 is a side elevation 45 of the body member, showing same attached to a post, also showing two of the detachable arms, which are each different with relation to each other, also showing a shelf and a pipe-line carried by said arms.

50 Figure 4 also shows a side elevation of the body members as attached to a post, the arms shown in Fig. 3 being omitted, and in place of one of them a third arm is substituted which is shown as carrying a shelf bracket. Figure 5 shows an end elevation 55 of the body alone, as attached to an upright

post. And Figure 6 is a top plan view of the inner end of either one of the arms.

Similar indices denote like parts throughout the several views.

In order that the construction, the operation, and the several advantages of my invention may be more fully understood and appreciated, I will now take up a detailed description thereof, in which I will set forth 65 the same as fully and as clearly as I may.

Referring now to the drawings in detail: Letter A denotes a post which is in the nature of pipe in this instance, round in cross section.

Numerals 1 and 2 denote the members of the body or base, said members being the base portions, each of which is adapted to extend half-way around the post A. Each of said base parts has bolt apertures 3—4 75 (shown only in Fig. 2) to receive the respective bolts 5 and 6 by which the portions 1 and 2 may be clamped tightly upon the post 1, as shown in the drawings.

Extending out to the right from the portion 1, integral therewith, is a projection having the upper shoulder 7 and the lower shoulder 8, the latter extending farther to the right than the shoulder 7. Formed in and on each side of said right-hand projection is a double socket, the members of which are divided by the web 9.

Said sockets open out to the side and also at the end between the shoulders 7 and 8. The shape of said sockets are substantially 90 as that shown by the web 12 in Figs. 2 and 4.

Likewise, extending out to the left from the portion 2, integral therewith, is a projection having the upper shoulder 10 and the lower shoulder 11, the latter extending 95 farther to the left than the shoulder 10, substantially as shown.

Formed in and on each side of said left-hand projection is a double socket, the members of which are divided by the web 12. 100 Said socket of the left projection opens out to the side and also at the end between the shoulders 10 and 11.

The shape of said left hand socket members are the same as that shown by the 105 web 12 in Figs. 2 and 4.

A plurality of detachable arms may be provided, only a few of which are shown in the drawings, as for instance, the long shelf-arm 13; the short pipe-arm 14; and the 110 bracket arm 15. Each of said arms is adapted to interlock with the body or base

members where it will be retained in place by gravity. Each of said arms 13, 14 and 15, has at its inner end a pair of spaced apart lugs or ears 16 and 17, which are identical with each other and each is of substantially the same size and shape as are the said webs in said right and left-hand projections of the base or body portions. The space between each pair of said lugs or ears being such as to receive its respective web, as the web 12.

The arm 13 is provided with a shoulder 18 to contact with the shoulder 7, and it is also provided with a shoulder 19 to contact with the shoulder 8, that is when the arm 13 is in operative position, as shown in Fig. 3, at which time the lugs 16—17 of the arm 13 are fitting in the sockets of the right-hand extension of the portion 1, and astride the web of said extension, corresponding with the web 12. In the upper edge of the arm 13 are the segmental indentations 20 and 21 in which lines of pipe may be laid to be supported by the arm 13. At the outer end of the arm 13 is an upturned tooth 22. A shelf B may be laid on the arm 13, extending from the tooth 22 to the post A, as shown in Fig. 3.

The inner end portion of the arm 15 is identical with the inner end of the arm B, the arm 15 having an upper shoulder 23 to engage with the shoulder 7, and a lower shoulder 24 to engage with the shoulder 8.

The outer portion of the arm 15 terminates in a tubular vertical bearing 25 to receive the stem 26, the latter extends down from the disc 27 and is concentric thereof, whereby the disc 27 is rotatably mounted and by which it may be removed simply by lifting it up, raising the stem 26 from out the bearing 25.

The arm 14 is merely in the nature of a hook adapted to support a pipe C, as shown, but its attachment to the body member is the same as that of the other arms shown.

Ordinarily there extend through a greenhouse, from end to end thereof, one or more lines of posts, as the post A, for supporting the roof of the house. In carrying out my invention it is proposed to secure to each of said posts one of the body members as shown in Fig. 1, which in itself being small it will not interfere or be unsightly. With the several body members in place, one or more on each post, we then have the basis for a great variety of combinations, certain of which I will mention: An arm 13 may be placed in position on each side whereby two shelves B may be provided, one on each side of the post A, or one of the arms 13 may support

two lines of pipe which may be laid in the indentations 20 and 21, and they may be used as a support for "flats" or boxes of plants, the other arm 13 still supporting a shelf B. One of the arms 13 may be replaced by an arm 14 to support a third line of pipe C. Or one or two of the arms 15 may be placed in position as in Fig. 4 and a pot may be placed on each of the discs 27 so used.

It is evident that various other combinations may be made with the arms 13, 14 and 15, and also other arms of different character may be substituted for one or the other or all of those shown.

It will be noticed that the said arms will be very secure, as they can not be removed without lifting up on their outer ends.

I also desire that it be understood that various changes and variations may be made in the several details of construction without departing from the spirit of the invention and without sacrificing any of the advantages thereof which are new and useful and which involve invention.

Having now fully shown and described my invention, what I claim and desire to secure by Letters Patent of the United States, is—

In combination with a vertical post, a two-part clamp, a pair of bolts for securing the two members of the clamp together around the post, an extension integral with each of said members and extending in directions opposite to each other and each having an upper shoulder and a lower shoulder, the lower shoulders being located further from the clamping members than the upper shoulders there being a double socket formed in each side of said extensions with the material of the extensions forming a web therebetween, a plurality of detachable arms, spaced apart lugs formed on the inner end portions of said arms and adapted to stride said webs, said lugs being adapted to fit in said sockets, shoulders formed on the inner end of each arm to contact with the respective lower shoulders of the extensions whereby the arms will be detachably supported in horizontal position and retained in interlocking connection with the extensions by gravity and adapted to be removed only by lifting upward on the outer ends of the arms, each of said arms having segmental spaced apart indentations in their upper edges to receive horizontal pipes therein whereby the pipes will be supported by said arms.

JOHN A. EVANS.
